UNITED STATES PATENT OFFICE.

HERMAN HERRENBRUCK, OF BELLEVILLE, ILLINOIS, ASSIGNOR TO ORBON STOVE CO.,
OF BELLEVILLE, ILLINOIS, A CORPORATION OF DELAWARE.

STOVE.

Application filed June 14, 1928 Serial No. 285,244.

This invention relates to stoves and has special reference to the stoves of that type in which the stove proper is enclosed within a casing, the walls of which are spaced from the walls of the stove proper to obtain a confined space in which the air is heated.

An object of the invention is to provide novel means for controlling the admission of air into the lower end of the casing at the front of the stove and comprising a hinged plate or door adapted for movement from open position in which air is freely admitted into the space in front of the stove to closed position when it is desired to remove the ashes or products of combustion from the stove.

Another object of the invention is to provide a spring actuator for the door or plate that is movable as aforesaid arranged in a relationship so that the power or resiliency of said actuator is utilized to hold the door or plate in closed position and also in open position, but which actuator will yield readily to permit movement of the door from either position to the other.

Another object of the invention is to provide an improvement of the character mentioned and as herein shown in a stove of the type disclosed in my co-pending application filed June 6, 1928, Serial No. 283,185.

Other objects will appear from the following description, reference being made to the drawing in which

Fig. 1 is a plan view of the invention embodied in a stove of the type mentioned.

Fig. 2 is a lateral side or end elevation, the supporting frame for the stove proper and a part of the casing being in vertical section from front to rear.

Fig. 3 is an enlarged vertical sectional view of the device.

Fig. 4 is a sectional view of the rigid stove supporting frame showing in end elevation the support for the hinged door controlling the admission of air to the stove casing.

My invention is embodied in a heating stove device comprising a rigid lower end frame made of an angle bar having a horizontal flange 1 extending inwardly from the lower edge of a vertical flange 2. A number of angle bars 3 have the ends of their horizontal flanges seated upon the ends of the horizontal flanges 1 at the ends of the frame and secured thereto by bolts 4. Plates 5 forming the walls of a casing for enclos-

ing the stove proper have their lower ends rigidly attached to the base frame.

The base 6 of the stove proper 7 is supported by legs or bosses 8 seated upon the angle bars 3 and secured and attached thereto by screws 9. Access is obtained to the inside of the ash chamber 10 of the stove proper through a hinged door 11 which may be opened to permit insertion and withdrawal of an ash pan or withdrawal of other contents of the ash chamber. The stove proper is spaced from all of the walls 5 of the casing and the lower end frame is open so that air may freely enter the casing around and about the stove.

The front casing wall 5 has a door opening 12 through which access may be had to the stove proper and to the ash compartment thereof. Below the door opening 12 a bar 13 is secured within the rigid supporting frame. This bar has lugs 14 seated upon the horizontal flange 1 and bolts 15 passing through said lugs and the flange 1 of the supporting frame and securing said parts together with the front edge of the bar 13 abutting against the inner surface of the flange 2 slightly below the upper edge of said flange 2. Door supporting legs 16 having holes 17 therein for the reception of door hinges (not shown) are formed on the bar 13 near the sides of the door opening 12.

This bar 13 extends rearwardly and has a flange or bead 18 along the upper side of its rear edge which extends under a flange or apron 19 extending downwardly from the front edge of the base 6 and provided with a longitudinal horizontal shoulder 20.

Arms 21 are formed integral with the ends of the bar 13 and the rear ends of said arms engage upon the shoulders 20. Thus, the bar 13 is strengthened and braced by engagement with parts of the stove proper. Webs 22 are formed integral with the bar 13 and the arms 21 and close the space between said parts at the ends of said bar. The rearwardly extending portion of the bar 13 has one or more large openings 23 therethrough for the passage of air into the stove enclosing casing at the front of the stove proper.

It is desirable to provide means for closing the openings 23 when ashes are being removed from the ash receptacle 10. For this purpose there is provided a door or plate 24 having aligned pivot projections 25 on its ends

engaged by hinge retaining clips 26 attached to the bar 13 by bolts 27. These pivot projections 25 are near the front edge of the door or plate 24 and permit swinging movement of said door or plate from position in which its rear edge seats upon the bar 13 in front of the flange or bead 18 to position in which said door or plate extends upwardly. When the door or plate 24 is in its upper position the openings 23 are open and permit free passage of air into the casing at the front of the stove proper. And when the door or plate 24 is in its lower position it will catch and retain any ashes or particles dropping from the ash pan being removed from the ash chamber 10 and prevent such ashes or particles from dropping to the floor of the room in which the stove is contained. These ashes or particles may be readily removed by sweeping or brushing.

The bar 13 has a longitudinal bead or flange 28 in front of the openings 23. The front edge of the door or plate 24 has a shoulder 29 designed and adapted to abut against the flange or bead 28 when said door or plate is in its open position and thus prevent movement of said door or plate beyond its intended open position.

A coil spring 30 has one end abutting against the rear wall of one of the openings 23 and supported by a lug 31, and the opposite end abutting against the rear or under side of the door or plate 24 and retained in position by a lug 32. The relationship of the parts is such that when the door or plate 24 is in its down or closed position the spring 30 will not move said door or plate from such closed position. And when the door or plate is started in a movement toward open position the spring 30 will exceed its power to actuate said door or plate through its final movements toward open position as soon as the door or plate passes a dead center line between the pivots 25 and the inner end of the spring 30.

The door or plate 24 is preferably provided with an engageable handle 33 to facilitate opening the same.

From the foregoing the nature and principle of the invention must be apparent, it being understood that the door or plate 24 is open when maximum heating service is desired, and may be kept closed when less than maximum heating service is needed and may also be closed to prevent dropping of ashes or particles onto the floor during removal of the ashes from the ash receptacle.

The invention may be varied in numerous respects without departure from the nature and principle thereof.

I do not restrict myself unessentially, but what I claim and desire to secure by Letters Patent is:—

1. A stove comprising an open supporting frame, a stove supported by said frame, a

casing enclosing said stove and having a door opening in the front side thereof, and a door controlling the rising of air through said frame at the front of said stove.

2. A stove comprising an open supporting frame, a stove supported by said frame, a casing enclosing said stove and having a door opening in the front side thereof, a door controlling the rising of air through said frame at the front of said stove, and an actuator for moving said door through its final movements toward open position.

3. A stove comprising an open supporting frame, a stove supported by said frame, a casing enclosing said stove and having a door opening, a support between the front part of said stove and the front part of said frame, and a door hinged to said support for controlling the admission of air into said casing at the front of said stove opposite said door opening.

4. A stove comprising an open supporting frame, a stove supported by said frame, a casing enclosing said stove and having a door opening, a support between the front part of said stove and the front part of said frame, a door hinged to said support for controlling the admission of air into said casing at the front of said stove opposite said door opening, and means for holding said door normally in open position to admit air into said casing at the front of said stove.

5. A stove comprising a rigid supporting frame, a casing in connection with said frame, a stove supported by said frame within and spaced from the walls of said casing, and means within said casing controlling the passage of air through said frame into said casing at the front of said stove.

6. A stove comprising a supporting frame, a stove supported on said frame, a casing enclosing said stove and having a door opening, a bar supported by said frame at the lower end of said door opening and having openings therethrough to admit air upwardly into said casing opposite said door opening and in front of said stove, and means for opening and closing said openings in said bar.

7. A stove comprising a supporting frame, a stove supported on said frame, a casing enclosing said stove and having a door opening, a bar supported by said frame at the lower end of said door opening and having openings therethrough to admit air upwardly into said casing opposite said door opening and in front of said stove, and a door hinged to said bar for opening and closing said openings in said bar.

8. A stove comprising a supporting frame, a stove supported on said frame, a casing enclosing said stove and having a door opening, a bar supported by said frame at the lower end of said door opening and having openings therethrough to admit air upwardly into said casing opposite said door opening and in

- front of said stove, a door hinged to said bar for opening and closing said openings in said bar, and an abutment for supporting said door in open position. 60
- 5 9. In a stove, a rigid supporting frame, a casing in connection with said frame and having a door opening, a stove supported by said frame within and spaced from said casing and having an ash receptacle opposite said door opening, an apron extending from said stove below said ash receptacle and opposite said door opening in said casing, and an element in said casing for cooperating with said apron to form a shelf between said ash receptacle and said door opening. 70
- 10 10. In a stove, a rigid supporting frame, a casing in connection with said frame and having a door opening, a stove supported by said frame within and spaced from said casing and having an ash receptacle opposite said door opening, an apron extending from said stove below said ash receptacle and opposite said door opening in said casing, and an element hinged in said casing and movable to 80 position to cooperate with said apron to form a shelf between said door opening and said ash receptacle. 85
- 15 11. In a stove, a rigid supporting frame, a casing in connection with said frame and having a door opening, a stove supported by said frame within and spaced from said casing and having an ash receptacle opposite said door opening, an apron extending from said stove below said ash receptacle and opposite said door opening in said casing, an element hinged in said casing and movable to position to cooperate with said apron to form a shelf between said door opening and said ash receptacle, and means for moving said element from said shelf-forming position. 95
- 20 12. In a stove, a supporting frame, a casing in connection with said frame and having a door opening, a stove mounted on said frame, an apron extending from said stove opposite said door opening, and means movable to and from a position to cooperate with said apron to form a shelf between said door opening and said apron. 100
- 25 13. In a stove, a frame, a casing supported by said frame and having a door opening, a stove supported by said frame and having an ash receptacle, an apron extending from said stove opposite said door opening, a member attached to said frame below said door opening and having its rear edge extending under said apron and having openings therethrough 105
- 30 in front of said apron, arms extending from said member and engaging upon said apron, and means supported by said element for opening and closing said openings. 60
- 35 14. In a stove, a frame, a casing supported by said frame and having a door opening, a stove supported by said frame and having an ash receptacle, an apron extending from said stove opposite said door opening, a member attached to said frame below said door opening and having its rear edge extending under said apron and having openings therethrough in front of said apron, arms extending from said member and engaging upon said apron, means supported by said element for opening and closing said openings, and a resilient device for holding said opening and closing means in open position. 70
- 40 15. In a stove, a frame, a casing in connection with said frame and having a door opening, a stove supported by said frame within said casing, an apron extending downwardly from said stove opposite said door opening, a bar attached to said frame below said door opening and extending under said apron and having openings therethrough in front of said apron, arms in connection with said bar engaging the upper side of said apron, webs connecting said bar with said arms, and a device movable to and from position to close said openings through said bar. 80
- 45 16. In a stove, a frame, a casing in connection with said frame and having a door opening, a stove supported by said frame within said casing, an apron extending downwardly from said stove opposite said door opening, a bar attached to said frame below said door opening and extending under said apron and having openings therethrough in front of said apron, arms in connection with said bar engaging the upper side of said apron, webs connecting said bar with said arms, a device movable to and from position to close said openings through said bar, and means for holding said device in position away from said openings. 95
- 50 17. A stove comprising a rigid open frame, a stove mounted on said frame, a casing in connection with said frame and enclosing said stove and spaced therefrom, a bar attached to said frame below said door opening and extending under the front of said stove and having openings therethrough, and means for closing said openings. 105
